UNITED STATES PATENT OFFICE.

THOMAS JOSEPH STURTEVANT, OF WELLESLEY, MASSACHUSETTS, ASSIGNOR TO
STURTEVANT MILL COMPANY, A CORPORATION OF MAINE.

CRUSHING-MILL.

1,105,712.

Specification of Letters Patent.

Patented Aug. 4, 1914.

Application filed May 31, 1913. Serial No. 770,960.

To all whom it may concern:

Be it known that I, THOMAS J. STURTEVANT, a citizen of the United States, residing at Wellesley, in the county of Norfolk 5 and State of Massachusetts, have invented or discovered certain new and useful Improvements in Crushing-Mills, of which the following is a specification, reference being had therein to the accompanying drawings.

10 This invention relates to certain improvements on the crushing mill of the Sturtevant U. S. Patent No. 857,121, dated June 18, 1907, the present invention having for its object to provide means whereby a certain 15 proportion of the crushed material may be discharged through a sample spout, as is sometimes desirable when it is necessary to ascertain the quality of the materials being crushed by separating a small percentage of 20 the material during a long continued run of the mill.

In the accompanying drawings Figure 1 is an elevation of the improved mill and Fig. 2 is a vertical sectional view thereof. 25 Fig. 3 is a plan view of the top section of the mill casing. Fig. 4 is a detail view of the double hinge bracket. Fig. 5 is a plan view of one of the swinging casing parts or sections. Fig. 6 is a detail view of a hopper for the sample spout. Fig. 7 is a detail section on line 7—7, Fig. 3.

Referring to the drawings, 12 denotes the base portion of the mill frame and which base portion is constructed to provide a 35 closed casing for housing the mill gearing, the said base or gear casing being bolted to supporting beams or timbers 13. The driving shaft 14 is journaled in suitable bearings 15 and 16 bolted, respectively, to the 40 gear casing and to the supporting timber frame-work structure, said driving shaft being provided with fast and loose pulleys 17 and 18 and with a bevel pinion 19 meshing with a bevel gear 20 provided with a 45 vertical sleeve 21 fitting a squared portion of the vertical shaft 22. The shaft 22 is stepped in a cupped bearing 23 supported on a lever or lighter-bar 24 which is adjustable in the usual manner for the purpose of 50 raising or lowering the shaft 22 and thus varying the relative positions of the crushing members to vary the degree of fineness of the output of the mill. The upper wall of the gear casing 12 is provided with an 55 upwardly projecting flange 25 which is over-

lapped by a downwardly projecting flange formed on a collar 26 mounted on the upper end of the sleeve 21, this construction affording a dust-lock which will exclude dust and grit from the vertical shaft 22 to protect the lower bearing of said shaft. 60

The upper section 27 of the mill frame or casing is mounted on the base or gear-casing section 12 and is firmly bolted thereto. This casing section 27 is constructed to form a 65 receptacle which receives and discharges the crushed material, and the upper end of the inner conical portion of the lower wall of said casing forms an upwardly projecting flange 28 loosely encircling the vertical shaft 70 22, said flange 28 being overlapped by a downwardly extending flange on a collar 29 on the said shaft 22, and preferably formed integral with scraper arms 30 rotating with the said shaft 22. These overlapping parts provide a second dust-lock. 75

The top portion of the casing of the mill is composed of two semicircular swinging door-like parts 31 and 32 each of which is separately hinged on pins 33 mounted on a 80 hinge bracket 34 bolted to the casing part 27. Mounted on the interior wall of these swinging door-like parts 31 and 32 are the corrugated stationary crushing liners 35 which coöperate with the crushing nut 36 85 on the upper end of the squared portion of the shaft 22 and fitting said squared portion so as to rotate with said shaft. This crushing nut is outwardly flared downwardly, corresponding somewhat in form 90 to the crushing liners 35 with which the said crushing nut coöperates in the crushing operation. By adjusting the lever or lighter-bar 24 the distance between the crushing nut and crushing liners may be 95 varied to vary the degree of fineness of the output of the mill, as will be understood.

The hinged casing part 31 is provided with a lug or projection 37 which is pivotally mounted on a latch yoke 38 adapted to 100 be swung into position to embrace a lug or projection 39 on the hinged casing part 32, said yoke being provided with a locking screw 40 operated by a hand wheel 41 so that said yoke may be secured in locking position 105 by means of said screw and hand wheel, and may be readily released or unlocked when desired, as will be evident. The hinged or swinging casing parts 31 and 32 are each provided at their upper parts with a semi- 110

circular recess 42 which affords a bearing for the upper end of the vertical shaft 22, and said bearing is preferably lubricated from an oil cup 43 mounted on one of said swinging casing parts.

Consumers of coal in large quantities frequently buy their coal at prices based on the fuel value thereof, and to determine this fuel value samples of a ton or more are frequently taken from a cargo often coming in a form requiring crushing as well as sampling. As hand sampling to secure fair samples from an entire cargo is a slow and somewhat difficult operation the present invention provides means whereby a sample, which may consist of any desired percentage of the run of fuel, may be obtained during the crushing operation. To this end the casing section 27 is provided with a sample discharge spout or opening 44 in addition to the regular discharge openings 45, said sample discharge opening communicating with a discharge spout 46. The regular discharge spouts or openings 45 slope outwardly from the base of the conical wall 47 of the casing part 27, while the entrance 48 from the chamber of the mill to the sample discharge opening 44 is raised considerably above the horizontal floor portion 49 of the chamber of the mill, and which floor portion represents the level from which the regular discharge openings 45 slope downward outwardly. This raised entrance 48 to the sample discharge opening 44 is afforded by a hopper 50 the inner part of which, as shown in Fig. 3, is curved to correspond to the curved path of movement of the lower end of the crushing nut, so that said crushing nut will discharge a certain amount of crushed material into the said hopper 50 during its rotation. The hopper or receiver 50 is preferably removably mounted in the mill chamber, and by providing hoppers of different sizes or lengths it will be obvious that the percentage of crushed material discharged from the sample spout, as compared with the entire output of the mill, may be varied. For example, the sample receiving hopper shown in Fig. 3 may represent a very large size of hopper, while the sample hopper shown in Fig. 6 may represent a small sized hopper adapted to receive and discharge a relatively small percentage of the crushed material.

By providing independent hinge pins for the swinging casing sections 31 and 32 greater strength is afforded as compared with the construction shown in Patent No. 857,121, herein before referred to, and in which both swinging casing sections are mounted on one pin, and provision is also made for independently adjusting the said swinging sections vertically so that they may be in proper positions for opening and closing the same without too much friction.

Such independent vertical adjustment may be effected by the use of thin washers 51 placed beneath the ears or lugs 52 on said swinging casing sections. In order to afford a proper locking engagement between these swinging sections 31 and 32 and the casing part 27 the said casing part is provided at its top with an annular locking flange 53 which is preferably outwardly flaring in cross section, as shown, and which fits corresponding recesses formed in the lower edges of the said swinging sections, so that these parts, when the said swinging sections are closed, will be in secure locking engagement with said casing part 27 and will, in the locking construction herein shown, be held down against the said casing part by wedging action, owing to the wedge-like form of the said flange and recesses. The material to be crushed may be fed to the mill through a hopper opening, as 54, formed in one of the said swinging casing sections.

The invention is not to be understood as being limited to the details of construction herein shown and described, as such details may be varied widely, within the province of mechanical skill, without departing from the scope of the invention.

Having thus described my invention I claim and desire to secure by Letters Patent:

1. In a crushing mill, a sampling spout communicating with the crushing chamber of the mill and adapted to receive and discharge a predetermined portion of the crushed material, and one or more discharge spouts adapted to take care of the remainder of the crushed material.

2. In a crushing mill, a sampling spout communicating with the crushing chamber of the mill and adapted to receive and discharge a predetermined portion of the crushed material, and one or more discharge spouts adapted to take care of the remainder of the crushed material, the entrance to the said sampling spout from the crushing chamber of the mill being above the level of the entrance or entrances from the chamber of the mill to the said discharge spout or spouts.

3. In a crushing mill, a sampling spout communicating with the crushing chamber of the mill and adapted to receive and discharge a predetermined portion of the crushed material, one or more discharge spouts adapted to take care of the remainder of the crushed material, and a removable hopper forming the entrance to said sampling spout.

4. In a crushing mill, a sampling spout communicating with the crushing chamber of the mill and adapted to receive and discharge a predetermined portion of the crushed material, one or more discharge spouts adapted to take care of the remainder of the crushed material, and a removable

hopper forming the entrance to said sampling spout, the top of said hopper being above the level of the entrance or entrances from the chamber of the mill to the said discharge spout or spouts.

5. A crushing mill provided with a sampling spout communicating with the crushing chamber of the mill and adapted to receive a predetermined portion of the crushed material, said spout extending outward so as to discharge the sampled moiety of the crushed material outside of the mill casing.

10. A crushing mill provided with a sampling spout communicating with the crushing chamber of the mill and adapted to receive a predetermined portion of the crushed material, said spout extending outward so as to discharge the sampled moiety of the crushed material outside of the mill casing, and a removable hopper forming the entrance to said sampling spout from the chamber of the mill.

15. A crushing mill provided with a sampling spout communicating with the crushing chamber of the mill and adapted to receive a predetermined portion of the crushed material, said spout extending outward so as to discharge the sampled moiety of the crushed material outside of the mill casing, and a

20. movable hopper forming the entrance to said sampling spout from the chamber of the mill.

25. A crushing mill provided with a sampling spout communicating with the crushing chamber of the mill and adapted to

receive a predetermined portion of the crushed material, said spout extending outward so as to discharge the sampled moiety of the crushed material outside of the mill casing, the entrance to said sampling 30 spout from the chamber of the mill being above the bottom of the crushing chamber.

8. A crushing mill provided with a sampling spout communicating with the crushing chamber of the mill and adapted to receive 35 a predetermined portion of the crushed material, said spout extending outward so as to discharge the sampled moiety of the crushed material outside of the mill casing, and a removable hopper forming the entrance to said 40 sampling spout from the chamber of the mill, the top of said hopper being above the bottom of the crushing chamber.

In testimony whereof I affix my signature, in presence of two witnesses.

THOMAS JOSEPH STURTEVANT.
